DEMODULATOR DEVICE FOR FREQUENCY
AND AMPLITUDE MODULATION

Edward H. Lange, Baltimore, Md.

Application April 28, 1943, Serial No. 484,937

22 Claims. (Cl. 250—20)

This invention pertains to thermionic demodulator devices for converting the pattern of frequency-modulation of a high-frequency carrier-voltage into corresponding output voltages, and more particularly to apparatus for compensating undesirable modifications introduced or superposed upon these output voltages by amplitude-modulation of the carrier-voltage; also for converting the pattern of amplitude-modulation of the carrier-voltage into corresponding output voltages.

The principal object of this invention is to provide such demodulator devices, employing a double-diode having a common cathode with two anodes, and employing the common cathode with a minimum of other control elements in a single thermionic enclosure, together with simple circuit means, providing these desired functions with economy of thermionic tubes and of component circuit elements.

A second object of this invention, is to provide demodulator devices, employing a single thermionic tube, and capable of simultaneously providing frequency-demodulation at one set of terminals and amplitude-demodulation at another set of terminals, from an impressed carrier-voltage having both frequency-modulation and amplitude-modulation.

A third object of this invention, is to provide a frequency-demodulator, employing a single thermionic tube, and wherein amplitude-limitation is employed, and having means for controlling the magnitude of the impressed voltage upon the limiting device when the output alternating current of the limiting device falls below the limit set for alternating output currents exceeding the limit-value.

A fourth object of this invention is to provide simple frequency-demodulation structures, capable of yielding output voltages directly proportional to frequency deviation from centre-frequency, with zero output voltage at centre-frequency, and with voltage of opposite polarities for frequencies above and below centre-frequency; also operable from a variety of magnitudes of impressed voltage, as distinguished from a fixed value set by a limitation device, and further, to provide in said simple structures means for compensating the effect of amplitude-variations upon the constant proportionality between the output voltage of frequency-demodulation and the frequency deviation from centre-frequency.

A fifth object of this invention is to provide in an amplitude-demodulator having a double-

diode with common cathode and two anodes, a simple frequency-deviation determining device, providing a positive unidirectional voltage for frequency deviations on one side of a centre-frequency, and negative unidirectional voltage for frequency deviations on the other side of the centre-frequency, whereby these frequency-determined unidirectional voltages furnish a control means for restoring undesired frequency deviations to a zero value, at the desired centre-frequency.

A sixth object of this invention is to provide compensation for amplitude-modulation in a frequency-demodulator having a double-diode with common cathode and two anodes, utilizing a control voltage derived from the total unidirectional current of both anodes; also to utilize this control-voltage either to modify the frequency-deviation sensitivity of a resonant circuit of the frequency-demodulator, or alternatively, to utilize this control-voltage to determine a cross-modulation in a balanced modulator, having a push-pull amplifier coupled to the resonant circuit.

A seventh object of this invention, is to provide a control-system wherein interconnection between the output terminals for frequency-demodulation and the output terminals for amplitude-demodulation is employed to furnish to an interconnected circuit a novel control of currents in this circuit, utilizing a universal demodulator of this invention.

These objects, and others, are hereinafter pointed out in further detail, and will be better understood by reference to the drawings, and to the appended claims.

In the drawings,

Fig. 1 illustrates a frequency-demodulator, having a thermionic tube containing a double-diode with common cathode and two anodes, a third anode having thermionic conductance with the common cathode, controlled by control-electrodes, a resonant circuit and a conductively connected choke-coil, the third anode and control-electrodes providing a limiting device for the magnitude of alternating current impressed upon the resonant circuit and choke-coil. The resonant circuit and choke-coil are capacitively coupled with the third anode, the frequency-demodulator having an output circuit coupled with the resonant circuit, and control means for regulating the resultant amplification of a preceding amplifier, when the alternating current impressed upon the resonant circuit and

choke-coil falls below the limit value, to which higher currents are limited.

Fig. 2 illustrates a universal demodulator, for both frequency-demodulation and amplitude-demodulation, having principal terminals for impressing modulated carrier-currents, a resonant circuit and conductively connected choke-coil capacitively coupled with the principal terminals, a thermionic tube having a double-diode with common cathode and two anodes, and a third anode having thermionic conductance with the common cathode, controlled by control-electrodes; also an output circuit for amplitude-demodulation, an output circuit for frequency-demodulation, and control means for compensating the effect of amplitude-variations in a resultant output voltage obtained from the output circuit for frequency-demodulation, the control means including coupling between the third anode circuit and the resonant circuit, for applying a cross-modulating voltage.

Fig. 3 illustrates another universal demodulator, and is a modification of Fig. 2, the resonant circuit being inductively coupled with the principal terminals, and the choke-coil which is conductively connected to the resonant circuit being capacitively coupled to the principal terminals; the control means for compensating the effect of amplitude-variations in a resultant output voltage obtained from the output circuit for frequency-demodulation, including coupling between the third anode circuit and the resonant circuit, as in Fig. 2, for applying a cross-modulating voltage.

Fig. 4 illustrates a universal demodulator, for both frequency-demodulation and amplitude-demodulation, having principal terminals for applying modulated carrier-currents, a resonant circuit and conductively connected choke-coil, the choke-coil being capacitively coupled with the principal terminals and the resonant circuit being inductively coupled with the principal terminals, a thermionic tube having a double-diode with common cathode and two anodes, a third anode with thermionic conductance to the common cathode controlled by control-electrodes, an output circuit for amplitude-demodulation, an output circuit for frequency-demodulation, and control means for compensating the effect of amplitude-variations upon the frequency-demodulated output voltage, the control means including coupling between the third anode circuit and the resonant circuit, for controlling the resultant conductance of the resonant circuit.

Fig. 1a illustrates a conventional thermionic amplifier for applying modulated voltages to the frequency-demodulator of Fig. 1, and illustrates an employment of the control means of Fig. 1 for controlling the voltage-bias of the control-grids of the amplifier.

Fig. 1b illustrates a characteristic of the limiter-device of Fig. 1, and the effect upon the characteristic of increased amplification in the preceding amplifier, determined by decreased negative-bias upon the amplifier control-grids, when the limiter output current falls below its limited value, and illustrates the lower threshold value of signal voltage at which the limit-value is reached.

Fig. 3a illustrates a type of mutual conductance characteristic for the thermionic tube of Fig. 2 and Fig. 3, and with reference to the third anode, common cathode, and control-grid of this tube, utilized for obtaining a compensating voltage for cross-modulation.

Fig. 3b illustrates a resistance coupled push-pull amplifier for use with the demodulators of Fig. 2 and Fig. 3, and for employment of the compensating voltage for cross-modulation.

Fig. 4a illustrates characteristics of circuit conductance, and superposed thermionic conductance between the third anode and common cathode of the tube of Fig. 4, in relation to negative-bias voltage upon the control-grid of this tube, and of total conductance variations necessary for compensating the effect of amplitude-variations upon the frequency-demodulation output.

Fig. 5 illustrates a circuit interconnected between the output terminals for frequency-demodulation and the output terminals for amplitude-demodulation, and a control-system utilizing the universal demodulators of this invention, wherein the currents of the interconnected circuit are determined by both the frequency-modulation and the amplitude-modulation impressed upon the carrier-wave, and applied to the demodulator.

Referring to Figs. 1-4 of the drawings, at 4 is shown a thermionic tube, having the double-diode consisting of the common cathode 3, with anodes 1 and 2, and having a third anode 5, a suppressor-grid 8, a screen-grid 7, and a control-grid 6; the third anode 5 has thermionic conductance with the common cathode 3, controllable by the electrodes 6, 7, and 8. At 32 is a source of unidirectional voltage, the negative terminal of which is connected to ground, at 44. Connected to anode 1, of the double-diode, is the serially connected high-frequency choke-coil 15 and stopping condenser 51, and likewise connected to the anode 2 of the double-diode, is the serially connected high-frequency choke-coil 14 and stopping condenser 41, and bridged between the condensers 41 and 51, is the output resistance 16, such that a circuit consisting of the resistance 16, choke-coils 14 and 15, and condensers 41 and 51, all in series, is connected between the anodes 1 and 2. The output resistance 16, is by-passed for the high or carrier-frequencies, by the condenser 61 which is connected to ground at 44, Figs. 1 and 4, and by condensers 61 and 61a connected to ground 44, Figs. 2 and 3.

Conductively connected to a resonant circuit, through a high-frequency choke-coil, is the common cathode 3, of the double-diode, conductively connected through a control-resistance 13; this series connection of cathode 3 through control-resistance 13 is continuous through high-frequency choke-coil 23 to resonant circuit 22-22', Figs. 1 and 2, or through high-frequency choke-coil 23a to resonant circuit 18a-19a-17, Figs. 3 and 4. Anodes 1 and 2, of the double-diode, are each conductively connected to the resonant circuit through a high resistance; anode 1 being connected through resistance 11 to a point p upon the resonant circuit 22-22', and anode 2 being connected through resistance 12 to a point q upon the resonant circuit 22-22', Figs. 1 and 2. In Figs. 3 and 4, anode 1 is connected through resistance 11 to a point p' upon resonant circuit 18a-19a-17, and anode 2 is connected through resistance 12 to a point q' upon resonant circuit 18a-19a-17. Resistance 11 is shunted by condenser 21a, and resistance 12 is shunted by condenser 21; likewise, resistance 13 is shunted by condenser 31. Resistances 11 and 12 are equal. At 9 and 10, are principal terminals for application of modulated carrier-voltages to the demodulator networks; terminal 9 is connected to

the positive terminal of the source 32 through a high-frequency choke-coil 27, Figs. 1 and 2, or through an inductance coil 26, Figs. 3 and 4. At 33 and 34 are by-pass condensers, for respectively by-passing high-frequency currents around the source 32, and for carrying high-frequency currents upon the screen-grid 7 directly to cathode 3, by a low impedance path. In the demodulators of Figs. 1 and 2, the resonant circuit 22-22' and conductively connected choke-coil 23, are capacitively coupled with the principal terminals, through condenser 29, Fig. 1, and through condensers 29 and 30, Fig. 2; in the demodulators of Figs. 3 and 4, the resonant circuit 18a-19a-17 is inductively coupled with the principal terminals, and the choke-coil 23a which is conductively connected to the resonant circuit 18a-19a-17, is capacitively coupled with the principal terminals, the capacitive coupling being through condenser 28, and the inductive coupling being through mutual inductance between coils 26 and 18a-19a.

Referring now to Fig. 1, the third anode 5, suppressor-grid 8, screen-grid 7, and control-grid 6, are utilized with the common cathode 3, for amplitude-limitation; there being several well-known circuit connections employing these control-elements to limit the amplitude of high-frequency signals applied to principal terminals 9, 10, such that beyond a certain threshold value of high-frequency voltage impressed upon the control-grid 6, the signal output will be substantially constant in amplitude, over a large range of input voltages, and such that the subsequent network can be utilized for response to frequency deviations, without the undesired effect of amplitude variations on this response. For this purpose, input terminals 9a and 10a are connected to a condenser 56a in series with a resistance 56, one terminal of resistance 56 being connected to the control-grid 6, and the other terminal of 56 being connected to cathode 3; also suppressor-grid 8 is connected to cathode 3, anode 5 is connected to source 32 through resistance 37, and screen-grid 7 is connected to a junction between resistances 35 and 36 in series, these series connected resistances being shunted across the source 32. Resistances 35 and 36 are for suitably proportioning the unidirectional voltage upon 7 in relation to the voltage of 32, and likewise resistance 37 is for suitably proportioning the unidirectional voltage upon 5 in relation to the voltage of 32. It will be understood that the present invention is not directly concerned with the connections employed for limitation of output from anode 5, but with the falling-off of such output below a threshold value of input voltage, characteristic of such limiting devices. The impedance of condenser 29 at the high or carrier-frequencies is negligible in comparison with that of the choke-coil 23 or resonant circuit 22-22', this condenser serving primarily as a stopping condenser to keep voltage of the source 32 from the diode-anodes, 1 and 2; likewise the impedance of condenser 31 at these frequencies is small in comparison with resistance 13. Condensers 21 and 21a likewise have impedances which are small in comparison with their respective shunted resistances 12 and 11 at the carrier frequencies; thus each of the parallel resistance-capacitance circuits 13-31, 12-21, and 11-21a, has a large time-constant in relation to the half-period time of the carrier frequencies, capable of smoothing out the unidirectional voltage across each of these circuits during the non-conductive half-cycle of the di-

ode, in a manner well understood. When the modulated voltage impressed upon 9a-10a is of sufficient magnitude to supply a limited output signal into 9-10, through the action of the limiting device, the voltages present across the resonant circuit 22-22' and conductively connected choke-coil 23, are varied by frequency deviations. The resultant alternating voltage across 23 and 18 thus acts upon anode 1, through the circuit p-11-1-3-10-13-23-18-p, and likewise the resultant alternating voltage across 23 and 19 acts upon anode 2 through the circuit q-12-2-3-10-13-23-19-q; it will be noted that the rectified current flows from 3 toward 23, through the control-resistance 13, that is, the total unidirectional current through both 18 and 19. At 57a is a variable contactor upon the control-resistance 13, for connection with the control-grids of a preceding amplifier, supplying alternating voltage for the terminals 9a-10a, as illustrated in further detail in Fig. 1a. The principles of operation of the structures, are considered in further detail hereafter.

Referring to Fig. 2, modulated signals are applied directly to the principal terminals 9-10; there being well known linkages for supplying frequency-modulated and amplitude-modulated currents to the principal terminals, for example, utilizing the source 32, choke-coil 27 and resistance 37 for connection to the anode-cathode of a preceding high-impedance pentode. In Fig. 2, operation does not take place upon a fixed magnitude of constant amplitude alternating current, fixed by a limitation device, but permits the usage of a wide variety of amplitudes. At 46 is a primary winding of a transformer, and at 47 is a secondary winding of this transformer; the transformer 46-47 is for the low or demodulated frequencies, that is, for the frequencies containing the signal-intelligence, which it is desired to separate from the high or carrier-frequencies. A variable resistance 45 is shunted across 46, and the third anode 5 is connected by the conductor 49 to a positive terminal of the source 32, the conductor 49 being connected to one terminal of resistance 45, and of winding 46, so that variations of current through anode 5 apply a corresponding voltage across primary 46, determined by resistance 45, and the current variations. Connected across the output resistance 16, is the primary coil 54, of a transformer 54-55 for the low or demodulated frequencies. The secondary 55 of this transformer, has a centre-tap O'', which is connected to one terminal of the secondary winding 47, the other terminal of 47 being connected to ground 44. The control-grid 6 is connected by the variable-contactor 51 to the control-resistance 13, which is connected to the cathode 3. The suppressor-grid 8 is connected directly to cathode 3 by conductor 8a, and the screen-grid 7 is connected by conductor 50 to a positive voltage upon the source 32. Cathode 3 is connected to ground, at 44, and shunted across the control-resistance 13 is the resistance 13a in series with condenser 13b, one terminal of resistance 13a being connected to ground by direct connection of this terminal to the terminal of 13, which is directly connected with the grounded cathode 3. At O' and A1, are output terminals for amplitude-demodulation voltages, and at F1 and F2 are output terminals for connection to the push-pull amplifier of Fig. 3b, F1 being connected to terminal 114, and F2 to terminal 115.

Referring to Fig. 3, low-frequency transformer

46—47 is connected in the same manner as in Fig. 2, and likewise low-frequency transformer 54—55 is connected in the same manner; the secondary 47 is connected to ground 44 at one terminal, and to centre-tap O' on 55 at the other terminal, the primary 54 is connected across the output resistance 46, and primary 46 is shunted by variable resistance 45, which is also connected to anode 5 at one terminal and to a positive voltage upon the source 32 by the other terminal, through conductor 49. Resistance 13 is likewise shunted by condenser 13b in series with resistance 13a, a common terminal of 13a and 13 being connected to the ground 44, the ungrounded terminal of 13 being connected to a terminal of choke-coil 23a. Control-grid 6 is connected to control-resistance 13 by the variable-contactor 57, and screen-grid 7 is connected to a positive voltage upon the source 32, by conductor 50. The conductor 8a connects the suppressor-grid 8 with cathode 3. The cathode 3 is connected to ground 44, through resistance 42, which is connected across a part of the voltage of source 32, at the grounded end of 32, and condenser 42a is connected to ground 44 from the conductor 52, which conductor connects the cathode 3 to the bias-resistance 42. By this means, a negative bias-voltage can be introduced upon control-grid 6, independent of voltages introduced upon 6 by control-resistance 13. Terminals O' and A₁ are for the output amplitude-demodulation voltages, and terminals F₁ and F₂ are output terminals for connection to the push-pull amplifier of Fig. 3b, F₁ being connected to terminal 114, and F₂ being connected to terminal 115, for obtaining amplified frequency-demodulation output voltages.

Referring to Fig. 4, suppressor-grid 8 is connected by conductor 8a to cathode 3, and screen-grid 7 is connected by the conductor 50 to a positive voltage upon the source 32. The third anode 5, is connected through a tertiary coil 26a to a positive voltage upon source 32, by conductor 53. Tertiary coil 26a has mutual inductance with the resonant circuit 18a—19a—17, for modifying resistance of 18a—19a—17. A bias-resistance 42 is connected across a part of source 32, at the grounded end 44, and cathode 3 is connected by conductor 52 to resistance 42. Conductor 52 is connected through condenser 42a to ground 44. Shunted across a part of the control-resistance 13, at the cathode-connected end of 13, is the primary 40, connected to 13 by the variable-contactor 57b. The primary coil 40 is a part of the low-frequency transformer 39—40. One terminal of secondary coil 39 of this transformer is connected to ground 44, and the other terminal is connected to the control-grid 6. By means of bias-resistance 42, a negative bias-voltage can be introduced upon the control-grid 6, independent of voltages introduced by the secondary 39. The resistance 13a has one of its terminals connected to ground 44, and the other of its terminals connected through condenser 13b to the terminal of resistance 13 opposite the cathode-connected terminal of resistance 13. Terminals O' and A₁ are output voltage terminals for amplitude-demodulation voltages, and terminals F₁ and O', are output voltage terminals for frequency-demodulation voltages.

Having described certain important features of the structures of this invention, other details will be apparent from the following discussion of the principles of operation of the devices. Referring to Figs. 1 to 4 inclusive, it will be noted

that the total unidirectional current of both anodes 1 and 2 of the double-diode, emerges from the cathode 3 and passes through the control-resistance 13. The current through anode 1 is determined by the magnitude of the vector sum of voltages across 23 and 18, and through anode 2, by the magnitude of the vector sum of voltages across 23 and 19, Fig. 1 or Fig. 2; likewise in Fig. 3 or 4, the current through anode 1 is determined by the magnitude of the vector sum of voltages across 23a and 18a, and through anode 2, by the magnitude of the vector sum of voltages across 23a and 19a. An important feature of this invention, is the utilization of this total unidirectional current in conjunction with a frequency-demodulating device having a double-diode with two anodes and a common cathode, for determining a unidirectional control-voltage directly proportional to the amplitudes of the input alternating currents to the demodulator networks, and independent of modification by frequency deviations, for compensating the undesirable effects of amplitude-variations upon the frequency-demodulation output voltages.

In order to utilize the control-resistance 13 for compensating effects of amplitude variation, it is essential that the unidirectional voltages developed across this resistance are not also modified by frequency deviations employed in the frequency-modulation, and for the entire range for which the frequency deviations are employed. The attainment of this purpose is not inherent in any resistance introduced in the circuit carrying the total unidirectional current of both diode-anodes, nor is it inherent in the employment of a specific resistance value, per se. It will be noted, for example by reference to the resonant circuit 22—22' and conductively connected choke-coil 23, Fig. 1 or 2, that even when the input alternating currents through 22—22' and 23 are constant in magnitude, the total unidirectional current through 13 will, in general, vary with frequency deviations. The further conditions eliminating dependence of the magnitude of total unidirectional current upon frequency-deviations from centre frequency, will be apparent from the following considerations.

The resonant circuit 22—22', consists of the variable condenser 17, together with the coils 18, 19, and 20. The coils 18, 19, 20, can be separate coils, or a single coil with terminals 22', p, 22, and q. The terminal 22 is located with reference to p and q, so that at resonance of the circuit to the centre-frequency, the voltages across p—22 and across 22—q, are equal. For a constant alternating current flowing through 22—22' and choke-coil 23, the voltage across 22—22' is in phase with the current at exact resonance to centre-frequency, and follows a circle-locus for frequency-deviations above and below centre-frequency, and with reference to the constant alternating current. The voltage across 23, is 90 degrees displaced from this current, and at exact resonance the voltages p—22 and 22—q are therefore displaced 90 degrees in phase from the voltage across 22—q, i. e., across the choke-coil 23. When the voltage across p—22 is directed toward 22, the voltage across 22—q is directed away from 22. Since the frequency deviations employed are but a small percentage of the carrier or centre-frequency, for the range of deviations employed the voltage across the choke-coil 23 is substantially constant. The resonant circuit is however sharply resonant, and the volt-

ages $p-22$ and $22-q$ are de-phased from their position at resonance, when the frequency is deviated. If for example, the voltage across $22-22'$ at resonance, is designated by E_r , and the voltage across the choke-coil 23 is designated by E_o , and the point p is at the half-voltage point upon $22-22'$, then the voltages at resonance across $p-22$ and $22-q$, are each $E_r/2$. The resultant voltages across $y-p$ and $y-q$, as the frequency is deviated on either side of the centre-frequency, are thus readily determined. When E_o is represented by a vector, then at exact resonance $E_r/2$ is a vector at the tip of E_o , and to the right of E_o , indicating the voltage across $p-22$, and likewise a vector $E_r/2$ at the tip of E_o and to the left of E_o , in opposite phase, indicates the voltage $q-22$. The loci of the voltages across $p-22$ and $q-22$, are along circles of diameter $E_r/2$, as the frequency is deviated. Thus at exact resonance, the resultant voltages at $y-p$ and at $y-q$, are equal. The unidirectional currents through the anodes 1 and 2 , are then equal, and there is no difference of potential between the anodes 1 and 2 resulting from the rectified currents. When the frequency is deviated, the voltage $y-p$ is greater than the voltage $y-q$, or vice versa, depending upon whether the deviation is positive or negative. The resultant voltage between anodes 1 and 2 , is thus of opposite polarity for positive frequency deviations in relation to the polarity for negative frequency deviations.

The total unidirectional current of both anodes, 1 and 2 , which passes through the control-resistance 13 , is determined by the arithmetic sum of the voltages across $y-p$ and across $y-q$, and the variation of this arithmetic sum with frequency deviations, for the entire useful range of such frequency deviations in the frequency-modulation, must be substantially eliminated in order to utilize the total unidirectional current of both diode-anodes, for compensating effects of amplitude variations of input alternating currents. This variation, is readily seen to be dependent upon the ratio of E_o to E_r employed, that is, upon the proportioning of the resonant circuit in relation to the voltage determining factors of the resonant circuit and the conductively connected choke-coil. For example, if the ratio E_o/E_r is designated by N , the sum of the voltages across $y-p$ and $y-q$ at resonance is designated by S_o , and the sum of the voltages across $y-p$ and $y-q$ for frequency deviations sufficient to de-phase $p-22$ and $q-22$ by 45 degrees is designated by S_d , then the percentage variations of S_o in relation to N , that is

$$100 \left(\frac{S_o - S_d}{S_o} \right)$$

are approximately as follows: When N is $\frac{1}{3}$, variation is 29.5 percent; when N is $\frac{1}{2}$, variation is 19 percent; when N is 1.00, variation is 7.6 percent; when N is 2.00, variation is 2.2 percent; and when N is 3.00, variation is 1.0 percent. It is therefore evident that by employing a ratio N sufficiently large, the effect of frequency deviation upon the total unidirectional current can be eliminated. The above illustration is given to aid in better understanding the effect of frequency deviation upon the total unidirectional current, when the input alternating current amplitude is constant; it is not to be understood as otherwise limiting the devices of this invention. When frequency deviations are employed, of magnitude less than sufficient to de-phase the voltages $22-p$ and $22-q$ by 45 degrees, the percentage varia-

tions will be correspondingly less, however frequency deviations capable of de-phasing by a substantial percentage of this amount are necessary to obtain adequate output voltages. A ratio of N equal to, or greater than 1.00, is therefore generally necessary.

Referring to Fig. 1, 1a, and 1b, the conductor $51a$ is carried to the grids 65 , 66 , and 67 of the amplifier, Fig. 1a, for example, through the respective impedances Z_1 , Z_3 , and Z_6 . Cathodes 68 , 69 and 70 , respectively of the thermionic tubes 62 , 63 , and 64 , are each connected to ground at 44 . The anodes of each of the tubes are understood to be connected to a source of positive voltage, such as 32 , the anode of tube 62 through impedance Z_2 , the anode of tube 63 through impedance Z_5 , and the anode of tube 64 through Z_7 . Impedances Z_2 and Z_3 are understood to have mutual impedance, likewise impedances Z_5 and Z_6 are understood to have mutual impedance; signal voltage having amplitude-modulation and frequency-modulation is understood to be applied to impedance Z_1 , and impedance Z_7 is understood to be coupled with the input terminals $9a-10a$, of the demodulator, Fig. 1. The control-grids 65 , 66 , and 67 , control the thermionic currents of the respective tubes 62 , 63 , and 64 , flowing between the respective anodes and cathodes of these tubes, and the mutual-conductance of each tube is understood to increase with a decrease in the amount of negative bias-voltage upon the control-grids. At 11, Fig. 1b, is a limiter characteristic, illustrating a relationship between alternating input voltages e_{gn} impressed upon the terminals $9a-10a$ from Z_7 , and the alternating output currents I_L of the limiter device, impressed upon the demodulator network, $9-10$. The axes 79 and 80 , are respectively for voltages e_{gn} and currents I_L . At 75 is indicated a constant value of I_L , such that when the input voltage e_{gn} exceeds a threshold value indicated by 71 , variations of I_L no longer take place with further large increases of e_{gn} . The above-noted conditions with reference to the ratio N having been met, for the resonant circuit and conductively connected choke-coil, the constant current I_L provides through the operation of the double-diode a constant unidirectional current in 13 , and a control-voltage at $51a$ of negative polarity with reference to the ground connection 44 . This negative-bias voltage is applied to the control-grids 65 , 66 , and 67 , and is unchanged for all voltages e_{gn} greater than the threshold value, at 71 . When however, the voltage e_{gn} falls to values less than the threshold value, by reason of amplitude-modulation present upon the signal voltage applied to Z_1 , the output current of the limiter device falls below the constant value of I_L at 75 , and the negative-bias voltage $-E_c$ upon the control-grids 65 , 66 , and 67 , is decreased, increasing the resultant amplification of the amplifier. The limiter characteristic is thereby modified, as shown at 72 , the threshold value being lowered to a position indicated by 76 . The equilibrium conditions resulting from such control of the amplifier bias, are apparent from the graphs 73 , and 74 , each representing the amplifier output voltage e_{gn} for a constant amplifier input voltage at Z_1 , as the negative-bias voltage $-E_c$ is independently varied. The negative-bias voltage at j , corresponding to the constant value of I_L of line 75 , is the normal negative-bias, and for the particular input voltage of graph 73 , the amplifier output voltage e_{gn} for this normal bias is indicated by $j-t$. When however, the negative-

bias voltage is reduced, for example to a point s , the amplifier output voltage is greater by the amount $n-s$, for the same input voltage. The intersection s of the limiter characteristic and the amplifier characteristic, determines an equilibrium, wherein the negative-bias voltage produced by the limiting device with control-resistance 13 , for the input voltage e_{gn} at equilibrium, is exactly equal to the negative-bias voltage required by the amplifier characteristic to yield this value of e_{gn} . Thus, for the particular constant input voltage upon Z_1 , represented by the graph 73 , if a fixed negative-bias indicated by j were used upon the amplifier, the input voltage upon the limiter would be as indicated by $j-t$, and the corresponding limiter output current would be as shown at h , whereas with the bias control the actual input voltage upon the limiter is increased by $n-s$, so that the limiter output current is raised from h to n . Similar equilibrium points are illustrated for the graph 74 , for a higher constant input voltage.

The condensers 21 , $21a$, and 31 , have low impedance for the high or carrier frequencies, in relation to the respective resistances which are shunted, and high impedance for the low or demodulation frequencies. Choke-coils 14 and 15 are high impedance coils for the high or carrier-frequencies, and have negligible impedance for the low frequencies of the demodulated voltages, likewise the condensers 41 and 51 serve to keep continuous voltage from the resistance 16 , and have negligible impedance for the low frequencies. The resistance 16 , is thus coupled with the resonant circuit which is connected to the diode-anodes 1 and 2 , and as heretofore pointed out, a difference of voltage is developed between anodes 1 and 2 by reason of unequal currents through equal resistances 11 and 12 , established by frequency deviations from centre-frequency. Voltages are thus established across the output resistance 16 , in accordance with the pattern of frequency deviations. By means of the bias-control, the threshold value of constant limiter current is lowered, in relation to operation with a fixed negative-bias voltage, and the effect of amplitude-modulation upon the currents supplied to the demodulator network annulled over an additional range, $76-77$.

Referring to Fig. 2 and Fig. 3b, the principal terminals 9 and 10 are understood to be supplied with high-frequency carrier-currents having frequency-modulation and amplitude-modulation; this is accomplished by well known thermionic linkages, for example by connection to a high-impedance pentode, the source 32 serving to energize the anode of the pentode connected to terminal 9 , the cathode of the pentode having a connection to ground 44 , and the modulated voltages being applied to the control-grid of the pentode. The type of mutual conductance characteristic employed, for the tube 4 , and control-grid 6 in relation to cathode 3 and anode 5 , is illustrated in Fig. 3a, at 78 , the ordinates of the graph along axis 85 indicating the mutual conductance, and the abscissas along axis 86 indicating magnitudes of negative-bias voltage upon control-grid 6 . The voltage difference indicated between lines 85 and 89 represents a fixed negative-bias voltage, when employed, the lines 85 and 89 being coincident when no fixed bias is used. The characteristic is attainable in thermionic tubes known as super-control tubes, or variable-mu tubes.

When the ratio N previously defined, has been

brought within the range necessary to eliminate modification of the total unidirectional current of anodes 1 and 2 , flowing through 13 , by frequency deviations, the total unidirectional current through 13 determines unidirectional voltages proportional to the amplitudes of the alternating currents supplied to the network. By means of variable-contactor 57 , upon 13 , a negative-bias voltage is introduced upon the control-grid 6 . When there is no amplitude-modulation present upon the terminals $9-10$, but only frequency-modulation, there is no variation of voltage upon control-grid 6 , and no voltage is transferred from primary 46 to secondary 47 . As previously discussed, frequency-demodulation voltages are then present upon resistance 16 , and applied to the primary coil 54 . These frequency-demodulation voltages are amplified by the push-pull amplifier, Fig. 3b, terminal F_1 being connected to 114 , and F_2 to 115 . In Fig. 3b, tube 101 has control-grid 113 , suppressor-grid 110 , screen-grid 112 , and anode 111 ; tube 102 has control-grid 106 , suppressor-grid 109 , screen-grid 107 , and anode 108 . The cathode 104 of tube 101 , and cathode 105 of tube 102 , are connected to a positive-voltage terminal of source 103 of bias-voltage, the negative terminal of 103 being connected to ground 44 . Suppressor-grids 110 and 109 are connected to the common connection between cathodes 104 and 105 , screen-grids 112 and 107 are connected together, and to the source 32 , by conductor 50 , and the anodes 111 and 108 are connected together by two equal resistances 99 and 100 in series, and energized by conductor 49 from source 32 , the conductor 49 being connected to the mid-point of the equal resistances 99 and 100 in series. Connected to anode 111 is condenser 95 , and connected to anode 108 , is condenser 94 . The unconnected terminals of condensers 94 and 95 are bridged by the two equal resistances 98 and 97 in series, the mid-point of this series connection being connected to ground 44 . Control-grid 113 is connected to terminal 114 , and control-grid 106 is connected to terminal 115 . Connected to terminal 16 , is the phase-inverting connection 96 upon resistance 97 .

When there is amplitude-modulation present upon terminals $9-10$, as well as frequency-modulation, the voltage-conversion sensitivity of the frequency-demodulation circuits is modified, and this modification must be compensated, otherwise the frequency-demodulation voltages will not correspond in pattern to the original frequency-modulation impressed upon the carrier-frequency. This has been usually accomplished by limiter-devices, that is by regulating the signal upon the demodulator circuit to a constant amplitude. Such usage does not permit utilizing a wide range of signal magnitudes, but requires a fixed input to the demodulator network, fixed by the characteristic of the limiter device. This disadvantage is overcome, in the demodulators of this invention, Figs. 2, 3, and 4. In Fig. 2, when the amplitude of alternating currents supplied to $9-10$ changes, the voltage upon control-grid 6 changes accordingly, and also the current through coil 46 . The resistance 45 employed, is small in relation to the reactances of coil 46 , and the varying voltage applied to coil 46 is determined primarily by the varying current through 45 . The secondary voltage in 47 , of the low-frequency transformer $46-47$, is applied to the centre-tap O'' of the secondary 55 , to cross-modulate the voltages applied by F_1 and F_2 to the termi-

nals 114 and 115 respectively, of the push-pull amplifier, acting as a balanced modulator. By this means variations introduced in the voltage across F_1 and F_2 by amplitude-modulation are compensated, the output voltages at 92 and 93 being frequency-demodulation voltages compensated for the effect of amplitude-modulation. Amplitude-demodulation voltages are taken off at the terminals O' — A_1 , corresponding to the voltage variations across the control-resistance 13.

In Fig. 3, a similar compensating means is employed for compensating the effect of amplitude variations upon the conversion sensitivity of the frequency-demodulator circuit, as above-described for Fig. 2. A fixed negative-bias voltage is provided by connection of cathode 3 to resistance 42, applying a fixed bias to control-grid 6, in series with the control-voltage applied from resistance 13, by way of circuit 3—52—42—44—13—57—6. This bias-voltage can be adjusted to set the axis 89 with reference to which the mutual-conductance is modified by voltages from the control-resistance 13, to adjust the relative changes of mutual-conductance effected by changes in amplitude of applied alternating currents, above and below an operating norm. The same amplifier, illustrated in Fig. 3b, is connected to F_1 and F_2 , terminal 114 being connected to F_1 , and terminal 115 to F_2 ; likewise amplitude-modulated and frequency-modulated alternating currents are supplied to terminals 9—10, as previously pointed out. The push-pull amplifier Fig. 3b, can be used alternatively, for amplifying amplitude-demodulation, by connecting terminal 114 to A_1 , Fig. 2 or Fig. 3, and by connecting terminals 115 and 116 together, to apply to control-grid 106 equal voltages of opposite phase to those applied to control-grid 113.

Referring to Fig. 4, the frequency-conversion sensitivity, whereby frequency deviations are converted into output voltages, is compensated for the effect of amplitude variation upon this sensitivity, by modifying the resultant conductance of the resonant circuit employed to impress voltages upon the double-diode, in a controlled relationship to the amplitudes of alternating currents supplied to the demodulator. A low-frequency transformer 39—40 has its primary coil 40 connected across a part of the control-resistance 13, between cathode 3 and an adjustable connection upon 13, adjustable by variable-contactor 57b. The secondary coil 39, has one terminal connected to the control-grid 6, and the other terminal connected to ground 44. Cathode 3 is connected by conductor 52 to bias-resistance 42, negatively biasing the control-grid 6, by way of the circuit 3—52—42—44—39—6. Anode 5 is supplied with positive voltage from the source 32, through tertiary coil 26a and conductor 53, the tertiary coil 26a being coupled by mutual inductance with inductance 18a—19a. The polarity of voltage applied to control-grid 6 by the secondary 39, is such that when the unidirectional current through 13 increases through corresponding increase of alternating current amplitudes of the high-frequency supplied to 9—10, the voltage impressed by 39 upon 6 will increase the conductance between anode 5 and cathode 3. Fig. 4a illustrates certain conductance relationships, with reference to the axis 81 along which conductance is measured, and the axis 82 along which negative-bias voltage on 6 is measured. At 90 is a line indicating the constant conductance g_0 , which is the tertiary shunt-equivalent

of the natural resistance of the resonant circuit, and between line 90 and the dotted line 87 are indicated various values of conductance between anode 5 and cathode 3, designated by g_p , and in relation to various values of negative bias-voltage upon control-grid 6. At 88 is indicated a resultant conductance g , of both the conductance g_p and g_0 for a fixed negative-bias voltage indicated by $-E_c$. By adjustment of the part of resistance 13 shunting the primary 40, employing 57b, the variation voltages introduced upon control-grid 6 by secondary coil 39, can be made to modify the resultant conductance in proper relationship to variations of amplitude of the high-frequency currents applied to 9—10, to maintain constant conversion sensitivity of the network to frequency deviations.

When there is no amplitude-modulation present upon terminals 9—10, but only frequency-modulation, the total unidirectional current through 13 is constant, the previously discussed proportioning of the voltage ratio N for choke-coil 23a and resonant circuit 18a—19a—17 having been carried out; there is then no variation voltage applied to the control-grid 6, and no modification of the resonant circuit other than the coupling with it of a constant thermionic conductance between 5 and 3. As previously discussed, frequency deviations from centre-frequency unbalance the currents of anodes 1 and 2, and establish voltage differences across 11 and 12, between the anodes 1 and 2, which are transmitted to the output resistance 16, and to terminals F_1 and O' , thereof O' being connected to ground 44. Amplitude-demodulation is taken off at terminals O' and A_1 , the resistance 13a being coupled with 13 through condensers 13b and 42a, which condensers have low impedance for the low or demodulation frequencies.

In order to aid in a better understanding of the principles employed in the compensating system of cross-modulation, Fig. 2 or Fig. 3, and Fig. 3b, and in the system of compensation by conductance control, Fig. 4, certain useful relationships are hereafter pointed out, with the understanding that these relationships are not to be construed as any manner of limitation upon the employment of the structures heretofore disclosed.

In the demodulator networks, employing a resonant circuit and conductively connected choke-coil to apply alternating voltages to a double-diode, the differential-voltage developed as a result of frequency-deviation from a centre-frequency for which the resonant circuit is tuned, is readily determined in terms of the magnitude of frequency deviations, the conductance of the resonant circuit, and the amplitude of high-frequency alternating currents supplied to the network; thus if the differential voltage developed between anodes 1 and 2, is designated by E_f , and the resultant shunted conductance of the tertiary circuit by g , and the amplitude of the alternating currents by I_a , then:

$$E_f = K \Delta f I_a / g^2 \quad (1)$$

in which K is a constant coefficient, and Δf the magnitude of frequency deviations from centre-frequency. In the system employing cross-modulation, the conductance of the resonant circuit is constant, and this relationship can be further simplified to:

$$E_f = K' \Delta f I_a \quad (2)$$

in which K' is a constant coefficient. In Figs.

2 or 3, the part of this voltage applied to each control-grid of the amplifier Fig. 3b is $E_f/2$, that is, half of the voltage is applied from O'' to F' , and half from F_2 to O'' . The compensating voltage applied by the secondary 47 is designated by e_a , and the resultant voltage applied to one of the control-grids of Fig. 3b is therefore:

$$e_a - E_f/2$$

and the resultant voltage applied to the other control-grid of Fig. 3b is:

$$e_a + E_f/2$$

The mutual-conductance characteristics of the tubes 101 and 102, are substantially identical, and straight line relationships with negative-bias voltage over the operating range used, the rate of change of mutual-conductance with bias-voltage being constant over the operating range, such characteristics being present in conventional tubes. In accordance with the well known resultant output voltage of such a balanced modulator, the output voltage produced at 92-93 is:

$$K_1 E_f (1 + k_1 e_a) \quad (3)$$

in which K_1 and k_1 are constant coefficients determined from tube and circuit constants, Fig. 3b. From the value of E_f of Equation 1, Equation 3 is transformed to:

$$K'_1 \Delta I_a (1 + k_1 e_a) \quad (4)$$

for the output voltage at terminals 92-93. The compensating voltage e_a must therefore be negative when the alternating current I_a increases above a norm, zero when the current I_a is equal to the norm, and positive when the current I_a falls below the norm, in order to provide operation equivalent to that of operating with a constant alternating current norm I_{ao} . This requires:

$$I_a (1 + k_1 e_a) = I_{ao} \quad (5)$$

The control-voltage produced at resistance 13, placed upon 6 by the voltage across 51-44, is directly proportional to the amplitude of alternating currents supplied to 9-10. Designating this control-grid voltage as E_{go} for the corresponding norm I_{ao} of alternating current, and as E_g for the corresponding current I_a which is variable above and below I_{ao} , then:

$$E_{go}/E_g = I_{ao}/I_a$$

also, the compensating voltage e_a is directly proportional to the variations of current through anode 5 to cathode 3, designated as i_p , so that $e_a = K_2 i_p$, K_2 being a constant coefficient. In view of these relations, the required equality of Equation 5 is converted to:

$$i_p = K_3 \left(\frac{1}{E_g} - \frac{1}{E_{go}} \right) \quad (6)$$

indicating the type of characteristic between control-grid negative-bias voltage and plate current to anode 5, required, the coefficient K_3 taking into account k_1 and K_2 , and a constant value of E_{go} . The type of mutual-conductance characteristic is readily determined from (6).

In the system of compensation employed in Fig. 4, wherein a resultant conductance is modified in relation to the magnitudes of high-frequency alternating currents supplied to the demodulator network, and to keep the conversion sensitivity constant, for the output voltage in relation to amount of frequency-deviation, the conductance g shunted across a tertiary coil in-

ductively coupled with the resonant circuit is two-fold in its effect. The conversion sensitivity is determined by the product of two factors: the magnitude of the voltage across the resonant circuit which is conductively connected to the choke-coil and double-diode, and the rate at which the voltage across this resonant circuit is de-phased from its resonant value by frequency-deviation; each of these factors is readily shown to be inversely proportional to the resultant conductance across the tertiary coil, the conversion sensitivity thus being inversely proportional to the square of the resultant conductance across the tertiary coil. Referring to Fig. 4a, there is illustrated at 91 a parabolic curve with reference to origin O_2 , removed from origin O_1 of negative-bias voltage, by an amount of negative-bias indicated by $-E_{co}$. This curve indicates a constant ratio between resultant conductance squared, that is g^2 , and decreasing negative-bias, such that $(E_{co} - E_c)/g^2$ is constant. As indicated by Equation 1, constant conversion sensitivity requires a constant ratio I_a/g^2 . The resultant conductance g is indicated in relation to negative-bias, by the ordinates between 82 and 87, when a characteristic such as 87 is employed for cathode-anode conductance 3-5; such characteristics are common in conventional thermionic tubes. It will be noted that a high degree of conformance exists with reference to the parabolic curve 91, and over a wide range of bias-variations about an operating conductance such as indicated at 88. Changes in negative-bias upon control-grid 6, are effected in proportion to changes in amplitude of alternating currents I_a with reference to a norm I_{ao} . By adjustment of 57b upon control-resistance 13, variations of negative-bias voltage upon 6 in relation to a fixed bias voltage can be adjusted, and compensation effected for a wide range of carrier amplitudes, each having a large amount of amplitude-modulation.

It will be evident, that a coil such as 26a can be coupled inductively with the resonant circuit 22-22' of Fig. 1, transformers 46-47, and 54-55 being dispensed with, and transformer 39-40 being similarly employed, as in Fig. 4, to control the negative-bias voltage upon control-grid 6. The coil 26a through which anode 5 is then connected, acts similarly to modify conductance of the resonant circuit 22-22', to compensate undesired effects of amplitude-variations in changing the conversion sensitivity of the circuit.

Referring to Fig. 5, an external circuit indicated by impedance Z_{af} is connected by variable-contactors 117 and 118 to the impedances Z_f and Z_a respectively, impedances Z_f and Z_a being connected in series, and having their common connection O' connected to ground 44. Z_f is an output impedance for frequency-demodulation, such as 16, Fig. 4, or either 97 or 98, Fig. 3b. Z_a is an output impedance for amplitude-demodulation, such as 13a, Figs. 2, 3, or 4. The relative magnitudes of voltages of frequency-demodulation and of amplitude-demodulation impressed upon Z_{af} are adjustable by the contactors 117 and 118, respectively. When the impedances Z_f and Z_a are a part of one of the universal demodulators of this invention, as above noted, e. g., Fig. 4, or Fig. 2, Fig. 3, and Fig. 3b, control of the currents in Z_{af} is effected simultaneously by both the frequency-demodulation voltages and the amplitude-demodulation voltages. As an example of such control, when a high-frequency carrier is impressed upon the demodulator, hav-

ing both amplitude-modulation and frequency-modulation, if both the amplitudes and the frequency of the carrier are modulated by the same low frequency, then the vector sum of voltages in Z_{af} is controlled by the phase-shift of the low frequency modulating the carrier frequency in relation to the same low frequency modulating the carrier amplitudes. If for example, the voltages of Z_f and Z_a are adjusted to equality by 117 and 118, then all magnitudes of voltages from zero to twice either of these voltages, are attainable upon Z_{af} , and controllable, by appropriate control of this phase-shift in the transmitted carrier.

In Figs. 2, 3, and 4, the third anode 5, and control-grid 6, screen-grid 7 and suppressor-grid 8 are employed with the common cathode 3, for compensating variations of the proportionality of frequency-demodulated voltages to magnitude of frequency deviations from centre-frequency, caused by amplitude-variations of the high-frequency carrier currents; this compensation is essential when it is necessary to reproduce a pattern of modulated carrier-frequency in the frequency-demodulation voltages. When however, it is required to provide only amplitude-demodulation, together with means for yielding a positive control-voltage for frequency deviations on one side of the centre-frequency, and a negative control-voltage for frequency deviations on the other side of the centre-frequency, for example for use in frequency stabilization, then the connections to the anode 5, suppressor-grid 8, screen-grid 7 and control-grid 6, can be dispensed with; these control-elements are then made available for other uses, only the common cathode 3, anodes 1 and 2 being required. Amplitude-demodulation is then provided across A_1-O' , and control voltages responsive to frequency deviation from centre-frequency are provided upon resistance 16, connected between the choke-coils 14 and 15.

In Fig. 1, condenser 59 serves to further reduce any voltages of carrier-frequency present upon 57a to a negligible value, without effecting the response upon 57a to low frequency variations of bias when the limiter output falls below its limit, by reason of low frequency amplitude-modulation.

It will be evident, that demodulator networks of the type illustrated in Figs. 3 and 4, can equally well be utilized with the limiter-device of Fig. 1, that is, the connection 57a can be similarly employed to regulate the bias of a preceding amplifier from control-resistance 13 of this type of circuit, the compensating means of Figs. 3 and 4 being of course omitted, and the anode 5, suppressor-grid 8, screen-grid 7, and control-grid 6 being connected as in Fig. 1. In Figs. 3 and 4, inductance coil 26 is tuned to the centre-frequency by condenser 25, in like manner to inductance coil 18a-19a, tuned by condenser 17. The centre-tap at 22a is understood to provide equal voltages across 22a-p' and 22a-q'; likewise the previously discussed voltage ratio E_a/E_r to apply to the ratio of voltage across 23a to voltage across p'-q'.

When the principal terminals 9-10, Figs. 2, 3, or 4, are supplied from a high-impedance pentode, the input impedance of the networks is very small in comparison with the anode-cathode variation resistance of the pentode, and changes of input impedance are also very small in relation to this resistance; the alternating currents supplied to the networks are thus substantially constant in proportion to the voltages applied to

the control-grid of the high-impedance pentode. In Figs. 1 and 2, the impedance of the circuit through coil 27 and resistance 37, is also high in relation to the impedance of 22-22-23.

Having described several illustrative embodiments of my invention, it will be evident that changes can be made in the form and arrangement of parts, and by substitution in part of other well-known structures, without departing from the spirit of my invention, as set forth in the appended claims, and I do not therefore limit the scope of the invention to such particular embodiments, or otherwise than by the terms of the appended claims.

What is claimed is:

1. In a demodulator-device, a thermionic tube having a double-diode with a first anode, a second anode, and a common cathode, a resonant circuit including an inductance coil, a tuning condenser connected across said coil, and connections between a first terminal and a second terminal upon said inductance coil, said connections including a first resistance connected from said first terminal to said first anode, a second resistance connected from said second terminal to said second anode, a third resistance bridged between the first and second anodes, said bridge including a serially connected first choke-coil and condenser between the first anode and one terminal of said third resistance, and a serially connected second choke-coil and condenser between the second anode and the other terminal of said third resistance, and condensers shunted across each of said resistances; a third choke-coil conductively connected from a third terminal upon said inductance coil at the half-inductance point between said first and second terminals, to said cathode, and a ground connection to said cathode.
2. In combination with the structure of claim 1, a control-resistance in series with said third choke-coil, between the cathode and said third choke-coil, and a condenser connected across said control-resistance.
3. In combination with the structure of claim 1, a third anode and a control-grid in said thermionic tube, said control-grid controlling thermionic conductance between the third anode and common cathode, a control-resistance in series with said third choke-coil, between said cathode and a terminal of said third choke-coil, a source of unidirectional current with negative terminal connected to ground, a first coupling means coupling said control-grid with said control-resistance, and a second coupling means coupling said third anode with a positive terminal upon said source, and with said resonant circuit.
4. A demodulator-device, having a thermionic tube containing a double-diode with a first anode, a second anode and a common cathode, and containing a third anode and a control-grid controlling thermionic conductance between said third anode and common cathode, a resonant circuit including connections to said first and second anodes and a first output-impedance connected between the first and second anodes; a choke-coil conductively connected from said resonant circuit to said cathode, a control-resistance serially connected between said cathode and said choke-coil, a ground connection to said cathode, a source of unidirectional current having the negative terminal connected to ground, a second output-impedance connected to said control-resistance, a first coupling means coupling said control-grid with said control-resistance, and

a second coupling means coupling said third anode with a positive terminal upon said source and with said resonant circuit.

5. A demodulator device, having a thermionic tube containing a double-diode with a first anode, a second anode, and a common cathode, a third anode, and a control-grid for controlling thermionic conductance between said third anode and the common cathode, a resonant circuit having connections to said first and second anodes and an output-impedance bridged across said first and second anodes; a choke-coil conductively connected between said resonant circuit and said cathode, a control-resistance serially connected between said choke-coil and said cathode, a ground connection to said cathode, coupling means for coupling said resonant circuit and the conductively connected choke-coil with amplitude-modulated and frequency-modulated carrier-currents, including a source of unidirectional voltage having a negative terminal connected to ground and a positive terminal connected to said third anode, and compensating means for compensating changes in the differential-voltage sensitivity of the resonant circuit and conductively connected choke-coil for frequency-deviations, effected by amplitude-variations of carrier-currents, said compensating means including coupling between said control-resistance and said control-grid.

6. In a demodulator-device for demodulating amplitude-modulated or frequency-modulated high-frequency alternating currents, a thermionic tube containing a double-diode with a first anode, a second anode, and a common cathode, a resonant circuit having a connection to said first anode, a connection to said second anode, and an output-impedance for frequency-demodulation bridged between said first and second anodes, a choke-coil conductively connected between said resonant circuit and said cathode, a ground connection to said cathode, coupling means for coupling said resonant circuit and choke-coil with a source of modulated high-frequency currents, and a control-resistance serially connected between said choke-coil and said cathode, shunted by capacitance, providing a unidirectional control-voltage upon said control-resistance, independent of frequency-modulation, and proportional to the amplitudes of said alternating currents.

7. In combination with the structure of claim 6, a third anode, a control-grid, a screen-grid, and a suppressor-grid in said thermionic tube, said grids controlling thermionic conductance between said third anode and the common cathode, and connections of said grids and third anode to said cathode, including a coupling between said control-resistance and said control-grid, compensating undesired modification of the differential-voltage sensitivity of said resonant circuit and connected choke-coil for frequency-deviations, effected by said amplitude-modulation.

8. In combination with the structure of claim 6, a third anode, a suppressor-grid, a screen-grid, and a control-grid in said thermionic tube, said control-grid controlling thermionic conductance of said third anode with said common cathode, a connection between said suppressor-grid and said cathode, said coupling means including a source of unidirectional voltage having a negative terminal connected to ground, a positive terminal connected to said screen-grid, and a positive terminal connected

to said third anode, and compensating means for compensating undesired changes in the differential-voltage sensitivity of the resonant circuit and connected choke-coil to frequency-deviations, effected by said amplitude-modulation, said compensating means including coupling between said control-resistance and said control grid.

9. A demodulator-device for frequency-demodulation and for amplitude-demodulation, having a thermionic tube containing a double-diode with a first anode, a second anode, and a common cathode, and containing a third anode, a suppressor-grid connected to said cathode, a screen-grid, and a control-grid, said grids controlling thermionic conductance between the third anode and said cathode, a source of unidirectional voltage having a negative terminal connected to ground and to said cathode, an output circuit including a resonant circuit, connections from said resonant circuit to said first anode and to said second anode, a choke-coil conductively connected to said resonant circuit and serially connected through a control-resistance to said cathode, a condenser shunted across said control-resistance, and a first output-impedance coupled with said first and second anodes; a second output-impedance coupled with said control-resistance, for amplitude-demodulation voltages, and compensating means for compensating the frequency-demodulation voltages upon said first output-impedance for undesired modification effected by amplitude-modulation, said compensating means including the connection of said screen-grid to a positive terminal of said source, the connection of said third anode to a positive terminal of said source, coupling between the control-grid and said control-resistance, and coupling between said thermionic conductance of the third anode and said output circuit.

10. In combination with the structure of claim 9, a common ground connection upon said first output-impedance and upon said second output-impedance.

11. In combination with the structure of claim 9, circuit means connected to said first output-impedance and to said second output-impedance, for combining frequency-demodulation voltages and amplitude-demodulation voltages.

12. A demodulator device for demodulating high-frequency carrier-currents having frequency-modulation and amplitude-modulation, having a thermionic tube containing a double-diode with a first anode, a second anode, and a common cathode, and containing a third anode; a suppressor-grid connected to said cathode, a screen-grid, and a control-grid, said grids controlling thermionic conductance between the third anode and cathode, a source of unidirectional voltage with a negative terminal connected to ground and to said cathode, an output circuit including a resonant circuit, connections from said resonant circuit to said first anode, and to said second anode, a choke-coil conductively connected to said resonant circuit and serially connected through a control-resistance to said cathode, a condenser shunted across said control-resistance, and a first output-impedance coupled with said first and second anodes, said choke-coil being proportioned in relation to said resonant circuit to provide a ratio of high-frequency voltages thereon respectively greater than unity; a second output-impedance coupled with said control-resistance, for amplitude-demodulation volt-

ages, and compensating means for compensating the frequency-demodulation voltages upon said first output-impedance, for modification of the differential-voltage sensitivity to frequency-deviation of the resonant circuit and choke-coil, by said amplitude-modulation, said compensating means including the connection of said screen-grid to a positive terminal of said source, the connection of said third anode to a positive terminal of said source, coupling between the control-grid and said control-resistance, and coupling between said thermionic conductance of the third anode and said output circuit.

13. In a demodulating device for demodulating frequency-modulated alternating currents, thermionic double-diode means having a first anode, a second anode, and a common cathode, resonant circuit means including an inductance coil for determining alternating voltages responsive to frequencies of said currents and responsive to amplitudes of said currents, a connection from said first anode to a terminal of said inductance coil through a first resistance, a connection from said second anode to a second terminal upon said inductance coil through a second resistance equal to said first resistance, a condenser shunted across said first resistance, a condenser shunted across said second resistance, a connection from the half-inductance point upon said inductance coil between said terminals to said common cathode, including a conductive impedance carrying the total thermionic current of both said anodes and having a large time-constant in comparison with the half-cycle period of said alternating currents, and filter means connected between said resistances, including an output-resistance for frequency-demodulated voltages.

14. A demodulator for demodulating frequency-modulated alternating currents, said demodulator having thermionic double-diode means with a first anode, a second anode, and a common cathode, resonant circuit means including inductance coil means for determining alternating voltages responsive to frequencies of said currents and responsive to amplitudes of said currents, a connection from said first anode to a terminal of said inductance coil means through a first resistance, a connection from said second anode to a second terminal upon said inductance coil means through a second resistance equal to said first resistance, a connection from an intermediate point upon said inductance coil means between said terminals to said common cathode, including a conductive impedance carrying the total thermionic current of both said anodes and having a large time-constant in relation to the half-cycle period of said alternating currents, filter means connected between said resistances including an output-resistance for frequency-demodulated voltages, and compensating means for compensating said frequency-demodulated voltages for amplitude variations of said currents, including a third anode having thermionic conductance with said common cathode, grid means for controlling said thermionic conductance, and a coupling means coupling said grid means with said conductive impedance.

15. A demodulator for frequency-modulated carrier currents, having a thermionic tube including a first diode-anode, a second diode-anode, and a common cathode, a third anode, and a control-grid for controlling thermionic currents between said common cathode and said third anode, resonant circuit means including inductance coil means for determining alternating volt-

ages responsive to frequencies of said carrier currents, a conductive impedance having a low power-factor at said carrier frequencies, a connection from said first diode-anode through a first resistance to a terminal of said inductance coil means, a connection from said second diode-anode through a second resistance equal to said first resistance, to a second terminal upon said inductance coil means, a connection from an intermediate terminal upon said inductance coil means between said terminals to said common cathode including said conductive impedance, filter means connected between said diode-anodes including an output-resistance for frequency-demodulated voltages, and means for impressing said carrier currents upon said resonant circuit means, including said control-grid and coupling between said resonant circuit means and said third anode.

16. In combination with the structure of claim 15, a thermionic amplifier having an output-impedance coupled with said control-grid, and a connection between grid control means of said amplifier and cathodes of said amplifier including a circuit through a part of said conductive impedance.

17. In combination with the structure of claim 13, a compensating means for compensating variations of the amplitude factor of said alternating currents, modifying said frequency-demodulated voltages, said means having a control-circuit including a path through said conductive impedance.

18. In a receiving system for frequency-modulation and amplitude-modulation, a demodulator device providing simultaneous frequency-demodulated voltages and amplitude-demodulated voltages, said device including a thermionic tube having a double-diode with a first diode-anode, a second diode-anode, and a common cathode, a third anode, and a control-grid for controlling thermionic currents between said common cathode and third anode, resonant circuit means determining alternating voltages in relation to said amplitudes and frequencies, connections between said resonant circuit means and said double-diode including a conductive impedance connected from said common cathode to said resonant circuit means, carrying the total thermionic current of both said diode-anodes, a first output-impedance for frequency-demodulated voltages coupled with said first and second diode-anodes, a second output-impedance for amplitude-demodulated voltages coupled with said conductive impedance, a common connection between said output-impedances, compensating means compensating said frequency-demodulated voltages for amplitude-modulation upon said resonant circuit means, including a control-circuit connected through said conductive impedance to said control-grid and circuit connections to said third anode, and a third output-impedance connected between said first and second output-impedances for currents determined by both said demodulated voltages.

19. In a demodulating device for demodulating frequency-modulated carrier-frequency voltages, resonant circuit means including inductance coil means for determining alternating voltages responsive to frequencies and to amplitudes of said carrier-frequency voltages, a first voltage-rectifying means including a first thermionic diode means serially connected with a first resistance, second voltage-rectifying means including a second thermionic diode means serially connected

with a second resistance equal to said first resistance, a junction between the negative rectified-voltage terminals of said voltage-rectifying means, a connection from a terminal of said inductance coil means to the terminal of said first rectifying means opposite said junction, a connection from a second terminal upon said inductance coil means to the terminal of said second rectifying means opposite said junction, a connection from said junction to an intermediate terminal upon said inductance coil means between said terminals thereon, including a third resistance shunted by a condenser, carrying the sum total thermionic currents of both diode means; thermionic amplifying means coupled with said resonant circuit means for energizing said resonant circuit means with carrier-frequency currents, including a control-grid means for applying said frequency-modulated carrier-frequency voltages, and a coupling means coupling said third resistance with said control-grid means for compensating the effect of variations of amplitude of said frequency-modulated voltages upon the demodulated voltages.

20. In a frequency-demodulator for converting frequency-modulated alternating voltages into amplitude-modulated voltages, having resonant circuit means responsive to frequencies and to amplitudes of said alternating voltages, and a thermionic voltage-rectifying means connected with said resonant circuit means including a resistance, for providing unidirectional voltages upon said resistance proportional to the amplitudes of said alternating voltages and independent of frequency-modulation, an energizing means for energizing said resonant circuit means with said frequency-modulated alternating volt-

ages, including a thermionic amplifying means coupled with said resonant circuit means and having a control-grid means for applying said frequency-modulated voltages, and a coupling means coupling said resistance with said control-grid means, for maintaining a constant ratio of conversion of frequency-deviations into output-voltages, independent of amplitude variations of said alternating voltages.

21. A frequency-demodulator device for demodulating frequency-modulated carrier currents, said device having a thermionic double-diode with a first anode, a second anode, and a common cathode, resonant circuit means including inductance coil means for determining alternating voltages responsive to said frequencies, a connection from a terminal of said inductance coil means to said first anode through a first resistance, a connection from a second terminal upon said inductance coil means to said second anode through a second resistance equal to said first resistance, a connection from an intermediate terminal upon said inductance coil means between said terminals to said common cathode, carrying the total thermionic current of both said anodes, an output-impedance for frequency-demodulated voltages, and connections between said resistances including said output-impedance and a filter-means.

22. In combination with the structure of claim 21, said connection from said intermediate terminal to said common cathode including a control-impedance, whereby unidirectional control-voltages are determined thereon by said total thermionic current.

EDWARD H. LANGE.
